INKING MECHANISM

Charles A. Wulf, Indianapolis, Ind.

Application October 20, 1930. Serial No. 489,881

15 Claims. (Cl. 101—169)

The present application relates to inking mechanism, and more particularly to mechanism used in connection with transferring a design, such as the grain of a piece of wood to a piece of metal or other material. Such mechanism consists primarily of an impression plate, means for spreading ink on said plate, and means, such as a roll of material of high elasticity and low resistance for transferring the ink from the impression plate to the article to be decorated. The primary objects of the present invention are to improve the means for spreading the ink on the impression plate, to provide novel means whereby a uniform deposition of ink on the plate may be attained, and to modify the usual construction of this type so as to conserve ink. Further objects of the invention will appear as the description proceeds.

To the accomplishment of the above and related objects, my invention may be embodied in the form illustrated in the accompanying drawing, attention being called to the fact, however, that the drawing is illustrative only, and that change may be made in the specific construction illustrated and described, so long as the scope of the appended claims is not violated.

In said drawing Fig. 1 is a plan view of inking mechanism constructed in accordance with the present invention;

Fig. 2 is a longitudinal section therethrough; Fig. 3 is a fragmentary sectional view of a detail on an enlarged scale;

Fig. 4 is a fragmentary transverse section; and Figs. 5 and 6 are fragmentary views of details, parts thereof being broken away.

Referring more particularly to the drawing, it will be seen that I have provided a bed indicated generally at 10 and comprising a base or backing board 11 supported by angle irons 12, one flange of each of said angle irons projecting upwardly above the board 11 and the other flange of each of said angle irons facing inwardly. As is illustrated particularly in Fig. 3, the bed is adapted to be mounted on an incline, the inclination being somewhat exaggerated in Fig. 3.

The parallel upstanding flanges 13 and 14 of the angle irons 12 form the side boundaries of the bed, and a cross piece 15 forms the boundary thereof at the upper end of said bed. An impression plate which, in the present instance, takes the form of a slab 16 of wood, and which may be a solid piece or may be built up, is mounted upon the base board 11 and is spaced from the flanges 13 and 14 to form troughs 17. Similarly, the impression plate 16 is spaced from the cross piece

15 to form a trough 18 communicating with the troughs 17. At its lower end, the impression plate 16 terminates some distance from the lower end of the backing board 11, and said end of the impression plate is bevelled, as at 19. The lower end of the backing board 11 is inclined upwardly away from the bevelled end 19 of the impression plate 16 to form a surface 20 which, with the flanges 13 and 14 and the end 19 of the impression plate, forms a well 21. As is obvious, the troughs 17 communicate with the well 21.

A carriage indicated generally at 22 comprises an axle 23 carrying grooved or flanged wheels 25; an axle 24 carrying similar wheels 26; and links 27 and 28 connecting the corresponding ends 70 of said axles. The wheels 25 and 26 are mounted to move upon the flanges 13 and 14, whereby the carriage is supported to move longitudinally of the impression plate, and is maintained at a uniform distance above said plate throughout 75 the length of said plate.

The links 27 and 28 are provided at aligned points intermediate their ends with inwardly facing sockets 29 adapted to receive the reduced trunnions 30 formed on the ends of a bar 31, 80 whereby said bar is oscillably mounted on said carriage 22. Supported on the bar 31 is a double edged blade 32. A backing member 33 is superimposed on said blade and a clamping bar 34 is mounted upon the upper surface of said backing member. The bar 31 is provided with a pair of spaced tapped bores 35 adapted to receive machine screws 36. Spacer collars 37 are sleeved on said screws, and the screws are turned down, thereby clamping the blade 32 and the backing 90 member 33 between the bars 31 and 34.

The screws 36 likewise secure to said bars a handle member 38, and a stop element indicated generally at 39 is adjustably secured to said handle bar 38.

The stop element 39 comprises a metal strip 40 having a projection 41, a second strip 42, and a pair of bolts 43, said bolts passing through apertures in the members 40 and 42 and clamping said members 40 and 42 to the handle bar 38. As 100 will be obvious, the stop element 39 is rotatably adjustable about the axis of the handle bar 38, and may be secured in any adjusted position. The projecting finger 41 is, as most clearly shown in Fig. 5, adapted to abut the axle 23 to limit 105 the oscillatory movement of the bars 31 and 34 and the blade 32 in a clockwise direction as viewed in Fig. 5.

While the operation of the above described device is thought to be obvious, it may be briefly 110

summarized as follows. The carriage 22 normally stands at the left end of Fig. 2 with the blade 33 resting against the inclined surface 20. The well 21 is filled with ink and, when it is desired 5 to ink the surface of the impression plate 16, the blade 32 is oscillated in a counter-clockwise direction to the position of Fig. 2. The carriage is then moved toward the right of Fig. 2 and, as the blade 32 passes through the well 21, it picks 10 up a quantity of ink, carries such ink up across the bevelled end 19 of the impression plate 16 and, as the carriage moves on toward the right end of Fig. 2, spreads the ink over the surface of the plate. It should be mentioned that the blade 15 32 is somewhat flexible, as is indicated in Fig. 5, so that the ink is carried smoothly and evenly over the surface of the plate. Any excess ink which tends to flow to the ends of the blade is caught by the troughs 17 and, due to the inclination of the bed, flows down said troughs into the well 21. At his option, the operator may or may 20 not carry the blade far enough to sweep excess ink into the trough 18 whence it can flow through the troughs 17 to the well 21.

25 Prior to my invention, a major difficulty encountered in operations with impression plates of this character lay in the fact that there was no means provided for regulating the pressure applied to the scraper in the finishing operation, 30 as a result of which fact an excess of ink might remain on the plate to cause a blurry transfer, or too much ink might be removed from the plate to cause an incomplete or a very faint transfer. Of course, it is to be understood, that perfect practice requires the removal of all ink from 35 the protruding portions of the plate and the retention of an optimum quantity of ink in the "grain" crevices.

Ink having been spread over the plate 16 by 40 the above described operation, the operator oscillates the blade 32 in a clockwise direction to bring it into the position of Fig. 5. To cause the blade to assume this position, the operator must press downwardly upon the bar 38 until 45 the finger 41 comes into contact with the axle 23, thus flexing the blade 32. He then moves the carriage 22 backwardly toward the left end of Fig. 2, sweeping ink off of the upstanding portions of the plate 16 and leaving just enough in 50 the "grain" crevices thereof. It will be obvious that the stop element 39 may be adjusted to provide exactly the required pressure of the blade on the plate, and that this stop element forces the operator to apply exactly the same pressure 55 to the plate during each sweeping operation.

If desired, a stop finger 44 may be attached to one of the links 27 or 28, and a cooperating stop lug 45 may be secured to the corresponding angle iron 12 to limit the movement of the carriage 22 in one or both directions.

I claim:

1. Inking mechanism comprising a bed provided with upstanding parallel side members, an impression plate mounted on said bed and spaced from said side members to provide troughs, an ink-receiving well at one end of said bed, said troughs inclining toward said well and communicating therewith, a carriage mounted for movement on said side members, and a scraper supported on said carriage and adapted to engage said plate and to be moved thereacross with said carriage.

2. Inking mechanism comprising a bed provided with upstanding parallel side members, an impression plate mounted on said bed and spaced

from said side members to provide troughs, an ink-receiving well at one end of said bed, said troughs inclining toward said well and communicating therewith, a carriage, flanged wheels for said carriage operatively mounted on said upstanding side members, and a scraper mounted on said carriage, said scraper being adapted to enter said well and to move, with said carriage, over said plate in contact therewith to carry ink from said well and to distribute the ink over the surface of said plate.

3. The combination with a bed provided with upstanding parallel side members, an impression plate mounted on said bed and spaced from said side members to form troughs, and an ink-receiving well at one end of said bed, said troughs inclining toward said well and communicating therewith, of a carriage mounted for movement on said side members, means oscillably mounted on said carriage and extending transversely of said plate, and a flexible blade carried by said means and adapted to be moved, by oscillation of said means, into and out of scraping relation with said plate.

4. The combination with a bed provided with upstanding parallel side members, an impression plate mounted on said bed and spaced from said side members to form troughs, and an ink-receiving well at one end of said bed, said troughs inclining toward said well and communicating therewith, of means for spreading ink from said well over said plate, said means comprising a carriage mounted for movement on said side members, and a flexible blade mounted on said carriage and extending across the width of said plate, said blade being oscillably mounted on said carriage whereby the edge thereof may be moved to enter said well and to drag on said plate as said carriage is moved.

5. The combination with a bed provided with upstanding parallel side members, an impression plate mounted on said bed and spaced from said side members to form troughs, and an ink-receiving well at one end of said bed, said troughs communicating with said well, of means for spreading ink from said well over said plate, said means comprising a carriage mounted for movement on said side members, a bar oscillably mounted on said carriage and extending transversely of said plate, a double-edged scraper blade mounted on said bar, the edges of said blade projecting beyond the lateral edges of said bar, a second bar superimposed on said blade, and means engaging said bars to clamp said blade therebetween.

6. The combination with a bed provided with upstanding parallel side members, an impression plate mounted on said bed and spaced from said side members to form troughs, and an ink-receiving well at one end of said bed, said troughs communicating with said well, of means for spreading ink from said well over said plate, said means comprising a carriage mounted for movement on said side members, a bar oscillably mounted on said carriage and extending transversely of said plate, a scraper blade mounted on said bar, a second bar superimposed on said blade, means engaging said bars to clamp said blade therebetween, said means securing to said bars a handle element, and a stop member mounted on said handle element to limit oscillation of said bars in one direction.

7. The combination with a bed provided with upstanding parallel side members, an impression plate mounted on said bed and spaced from said

- side members to form troughs, and an ink-receiving well at one end of said bed, said troughs communicating with said well, of a carriage mounted for movement on said side members, 5 means oscillably mounted on said carriage and extending transversely of said plate, and a flexible double-edged blade carried by said means and adapted to be moved, by oscillation of said means, to bring either of its edges into scraping relation with said plate. 8. The combination with a bed provided with upstanding parallel side members, an impression plate mounted on said bed and spaced from said side members to form troughs, and an ink-receiving well at one end of said bed, said troughs communicating with said well, of means for spreading ink from said well over said plate, said means comprising a carriage mounted for movement on said side members, a bar oscillably mounted on said carriage and extending transversely of said plate, a double-edged scraper blade mounted on said bar and extending laterally beyond both sides of said bar, a second bar superimposed on said blade, means engaging said bars to clamp said blade therebetween, said means securing to said bars a handle element, and a stop member mounted on said handle element to limit oscillation of said bars in one direction. 9. In a device of the class described, a bed inclined from one end to the other, upstanding side members on said bed, an upstanding end member at the upper end of said bed, an impression plate mounted on said bed and spaced from said side members and from said end member to form communicating troughs and spaced also from the lower end of said bed, means at the lower end of said bed providing a surface sloping upwardly away from the adjacent end of said impression plate to form an ink-receiving well with which said troughs communicate, and means mounted on said side members for scraping ink from said well over the surface of said impression plate. 10. In a device of the class described, a bed inclined from one end to the other, upstanding side members on said bed, an upstanding end member at the upper end of said bed, an impression plate mounted on said bed and spaced from said side members and from said end member to form communicating troughs and spaced also from the lower end of said bed, means at the lower end of said bed providing a surface sloping upwardly away from the adjacent end of said impression plate to form an ink-receiving well with which said troughs communicate, a carriage movably mounted on said side members, and a scraper blade carried on said carriage and oscillable about an axis transverse to the direction of movement of said carriage, said blade being adapted to spread ink from said well over said plate. 11. In a device of the class described, a bed inclined from one end to the other, upstanding side members on said bed, an upstanding end member at the upper end of said bed, an impression plate mounted on said bed and spaced from said side members and from said end member to form communicating troughs and spaced also from the lower end of said bed, means at the lower end of said bed providing a surface sloping upwardly away from the adjacent end of said impression plate to form an ink-receiving well with which said troughs communicate, a carriage movably mounted on said side members, and a double-edged scraper blade oscillably mounted on said carriage on an axis transverse to the direction of movement of said carriage, said blade being movable to bring its one edge into contact with said plate while said carriage moves in one direction to spread ink from said well over said plate, and movable to bring its opposite edge into contact with said plate while said carriage moves in the opposite direction to remove excess ink from said plate. 12. In a device of the class described, a bed inclined from one end to the other, upstanding side members on said bed, an upstanding end member at the upper end of said bed, an impression plate mounted on said bed and spaced from said side members and from said end member to form communicating troughs and spaced also from the lower end of said bed, means at the lower end of said bed providing a surface sloping upwardly away from the adjacent end of said impression plate to form an ink-receiving well with which said troughs communicate, a carriage movably mounted on said side members, a double-edged scraper blade oscillably mounted on said carriage on an axis transverse to the direction of movement of said carriage, said blade being movable to bring its one edge into contact with said plate while said carriage moves in one direction to spread ink from said well over said plate, and movable to bring its opposite edge into contact with said plate while said carriage moves in the opposite direction to remove excess ink from said plate, and means for limiting the degree of pressure of said blade on said plate in said last-mentioned direction of movement. 13. In a device of the class described, a bed inclined from one end to the other, upstanding side members on said bed, an upstanding end member at the upper end of said bed, an impression plate mounted on said bed and spaced from said side members and from said end member to form communicating troughs and spaced also from the lower end of said bed, means at the lower end of said bed providing a surface sloping upwardly away from the adjacent end of said impression plate to form an ink-receiving well with which said troughs communicate, a carriage movably mounted on said side members, a double-edged scraper blade oscillably mounted on said carriage on an axis transverse to the direction of movement of said carriage, said blade being movable to bring its one edge into contact with said plate while said carriage moves in one direction to spread ink from said well over said plate, and movable to bring its opposite edge into contact with said plate while said carriage moves in the opposite direction to remove excess ink from said plate, and means movable with said blade and adjustable with respect thereto and engageable with an element of said carriage for limiting the degree of pressure of said blade on said plate in said last-mentioned direction of movement. 14. In a device of the class described, an impression plate, adapted to receive a coating of ink, and means for scraping excess ink from said plate, said means comprising a carriage, means rigid with said plate for guiding said carriage, a blade mounted on said carriage and movable with respect thereto to engage said plate, and means movable with said blade and adjustable with respect to said blade for limiting the degree of movement of said blade in a direction to engage said plate. 15. In a device of the class described, an impression plate, adapted to receive a coating of ink,

and means for scraping excess ink from said plate, said means comprising a carriage, means rigid with said plate for guiding said carriage, a blade carrier oscillably mounted on said carriage and including a bar extending transversely of said carrier, a flexible blade carried by said carrier and movable therewith to engage said plate with a flexing pressure, a clamp secured to

said bar and optionally adjustable about the axis of said bar, a tongue carried by and movable with said clamp, and a stop element rigid on said carrier, said tongue being engageable with said stop element to limit oscillation of said carrier in one direction. 80
